CLAIM

The ornamental design for a grill mat, as shown and described.

DESCRIPTION

FIG. 1 is a first perspective view of a grill mat showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The evenly spaced broken lines in the drawings illustrate portions of the grill mat which form no part of the claimed design. The long dash, short dashed broken lines show enlarged portions of the design and form no part of the claimed design.

1 Claim, 10 Drawing Sheets
